END MILL GRINDERS

Harold K. Gumphrey, Plymouth, Wis.

Application August 3, 1953, Serial No. 371,912

4 Claims. (Cl. 51—101)

This invention relates to grinders, and more particularly to a grinder adapted to grind a cutting edge of an end mill cutter, or the like.

It is an object of the present invention to provide a grinder which will grind all cutting edges of an end mill in a single pass of the wheel.

Another object is to provide a grinder which will grind the cutting edges of an end mill more uniformly.

Another object of the invention is to provide a grinder which will grind the cutting edges of an end mill more rapidly.

A further object is to provide a grinder for an end mill which will reduce the surface temperature resulting from grinding.

A still further object of the invention is to provide a grinder for an end mill, or the like, which may be used in conjunction with the grinding wheel of a common surface grinder.

A still further object is to provide a grinder for an end mill which may be adjusted to accommodate any pitch of cutter.

A still further object is to provide a grinder for an end mill, or the like, which will automatically advance or retard the rotation of the arbor in response to the lead of the cutter.

Still further objects will become apparent upon considering the following specification, which, when taken in conjunction with the accompanying drawings illustrates a preferred form of the invention.

In the drawings:

Fig. 1 is a top plan view of a grinder made in accordance with the present invention;

Fig. 2 is a side elevational view of the grinder shown in Fig. 1, parts thereof being broken away to more clearly illustrate certain other parts;

Fig. 3 is a transverse cross-section taken on the line 3—3 of Fig. 2, looking in the direction of the arrows;

Fig. 4 is an end elevational view of the grinder as seen from the left in Fig. 1;

Fig. 5 is an end elevational view of the grinder as seen from the right in Fig. 2, and showing the relation between a two blade cutter and a grinding wheel; and

Fig. 6 is a cross-section taken on the line 6—6 of Fig. 2, looking in the direction of the arrows.

Referring to the drawings, and particularly to Fig. 2, the end mill grinder is built on a base 10, which has a dove-tailed groove 11 (Fig. 3) therein. The groove 11 receives a tongue 13 of a sliding table 15. The table 15 is composed of a lower section 15' slidable on the base 10 and an upper part 15" joined to the lower portion by hinges 17—17 and slidable therewith. A spring 18 (Fig. 4) is mounted between the sections 15' and 15" and tends to maintain them separated.

The upper table section is formed with a forward pedestal 20 and a rear pedestal 22. The pedestals 20 and 22 have aligned bearings therein which receive an arbor shaft 24, the arbor shaft being supported between a pair of thrust bearings 25—25 in the pedestal 20. The

forward end of the arbor shaft 24 retains an end mill 26 which is to be ground or reground. The arbor shaft 24 is rotatable in the pedestals 20 and 22 but is held in fixed axial position relative thereto by the thrust bearings 5 25—25.

A collar 27 is mounted on the shaft 24 and has a cam follower or pin 28 projecting inwardly from the inner diameter of the collar and engageable with a helical groove or cam 30 in the shaft 24. The collar has a reduced diameter, as seen at 31, which receives a U-shaped yoke 33 (see Fig. 3), the yoke being adapted to move the collar 27 axially along the arbor shaft 24.

The base of the yoke 33 is formed with a cylindrical pedestal 35 which is received in a similar cylindrical recess in a block 36. The block 36 has a groove 37 which is received over a tongue 38 in a transversely movable block 40. The block 40 has a groove 42 (Fig. 3) extending at right angles to the tongue 38. The groove 42 receives a tongue 45 on an adjusting block 47. The block 20 47 is pivotally connected to the upper plate 15" of the table 15 by a pivotal screw 47' and may be clamped in adjusted position by set screws 48—48 operating in arculate T slots 48'. The block 40 is circular in cross-section and is received in a circular opening in a square collar 49. The collar 49 is restrained from moving longitudinally relative to the base 10 by rails 50—50 but is free to move transversely along the rails 50—50. The rails are supported by posts 51—51 carried on the top of the base 10 and secured thereto by bolts 52—52, or 30 equivalent fastening means.

Since the rails 50 prevent movement of the block 40 axially of the arbor shaft 24 while permitting its movement transversely thereof it follows that as long as the tongue 45 is parallel to the arbor shaft 24 there will be 35 no relative movement between the base 10 and the yoke 33, and therefore as the table 15 slides, the pin 28 will remain stationary relative to the base 10 as the arbor shaft 24 moves, causing the arbor shaft 24 to turn with the groove 30.

Similarly, for each angular setting of the block 47 according to a scale S the block 40 is moved a definite distance either to the right or left of the axis of the machine. Any movement of the block 40 to the right or left causes a relative movement of the block 36, effecting a change in the distance the yoke moves, and hence causes a change of pitch on the arbor shaft 24. Thus the true pitch may be marked on the scale S.

The yoke 33 has a bracket 53 formed on its upper end, the bracket 53 forming a support for a motor 55. The motor 55 has a gear 57 fixed on its shaft, the gear 57 driving a second gear 58. The gear 58 is mounted on the arbor shaft 24 and is fixed to the collar 27 to rotate the arbor shaft constantly during the grinding operation.

The gear 58 is fixed to a sleeve 60 which is received on the arbor shaft 24 and extends through the bearing in the pedestal 22. The sleeve 60 receives a cam 64 which has a number of nodes or high points 65 thereon (Fig. 4) which correspond in number to the number of cutter edges on the end mill 26. The cam 64 may be adjusted and fixed circumferentially on the sleeve 60 so that the nodes 65 occur opposite cam followers 67 as the cutting edges of the end mill pass the grinding wheel 68.

The cam follower 67 is mounted for both rotational and axial movement on a shaft 69 so that the cam follower 67 can follow the axial movement of the cam 64. The cam follower 67 has radially extending flanges 70 which envelop the sides of the cam 64 to insure constant contact between the cam and follower.

The shaft 69 is carried in a standard 72 formed on the lower plate 15' of the table 15 so that contact of the high point or node 65 of the cam 64 by the follower 67 com-

presses the spring 18 and moves the end mill 26 into engagement with the grinder 68.

The grinder 68 may form an integral part of the present apparatus in which case it is mounted from the base 10, or if desired, a grinding wheel of a convenient surface grinder may be utilized.

Operation

In operation, the end mill 26 which is to be ground or sharpened is placed in the end of the arbor shaft 24 and secured therein as by a machine screw 75.

The scale S on the block 47 may then be set for the correct pitch of the cutter edges. A cam 64 having the same number of nodes 65 as there are cutting edges on the end mill 26, is selected and placed on the outer end of the sleeve 60. The cam 64 is adjusted so that when the grinding wheel contacts the cutting edge of the end mill, the follower 67 will be on the node 65 of the cam 64. At the same time the grinding wheel 68 is adjusted to make a cut of the desired depth.

When the machine is thus adjusted the motor 55 and the grinding wheel motor (not shown) are both started. The motor 55 drives the gear 58 through the pinion 57. The gear 58, being connected to the collar 27, rotates the collar 27 which in turn rotates the shaft 24 through the pin 28.

Simultaneously, the gear 58 rotates the sleeve 60 which in turn rotates the cam 64. The cam 64 acts against the cam follower 67 to force the end mill 26 against the grinding wheel 68 as each cutting edge of the end mill 26 passes the grinding wheel 68.

The sliding table 15 may then be reciprocated longitudinally on the base 10. As the table 15 slides back and forth, the rails 50 act against the collar 49 to prevent longitudinal movement of the sliding block 40, but permit transverse movement of the block in response to the angle at which the adjusting block 47 is set.

The transverse movement of the block 40 causes a longitudinal movement of the block 36 which in turn moves the pin 28 longitudinally in the slot 30 to vary the position of the pin 28 in the slot and thus effect rotation of the shaft 24 independently of the motor 55. This independent rotation of the shaft 24 is regulated by setting of the adjusting block 47 to the pitch of the particular end mill 26 being ground, so that the cam 64 always acts to advance the mill onto the grinding wheel in position to grind the cutting edge of the mill.

It will be realized that the hereinbefore described form of the invention is given merely as a preferred example thereof and that various changes in size, shape and arrangement of parts may be made without departing from the spirit of the invention or the scope of the subjoined claims.

That which is claimed as new and is desired to be secured by United States Letters Patent is:

1. In a tool grinder, a base, a grinding wheel mounted on said base to grind a tool having cutting edges, a table slidably longitudinally on said base, a pair of spaced pedestals carried by said table, an arbor shaft rotatably mounted between said pedestals, said shaft having a helical cam cut therein, a collar mounted on said shaft to reciprocate axially thereon, a cam follower mounted in said collar and projecting inwardly into engagement with said cam, means to rotate said collar to drive said shaft through said follower, means on said table co-operating with means on said base to vary the axial motion of the collar as the table reciprocates to rotate the collar relative to the arbor shaft to vary the rotation of the shaft as the

latter rotates, and means to move the tool against the grinding wheel to grind the cutting edges of the tool.

2. In a tool grinder, a base, a table mounted for reciprocating movement on said base, a pair of spaced pedestals formed on said table, an arbor shaft having a fixed axial position relative to said table and rotatably mounted between said pedestals and adapted to secure a tool to be ground, said arbor shaft having a helical cam therein, a collar mounted about said shaft, a cam follower projecting inwardly from said collar and into engagement with said cam, a gear fixed concentrically on said collar to drive the shaft through said follower, a motor mounted adjacent said collar, a gear carried by said motor and in engagement with said first named gear, a yoke supporting said motor and engaging said collar to move the collar longitudinally and effect movement of the follower in the cam to vary the rotation of the arbor shaft independently of the motor as the table is reciprocated on the base, and means on said base cooperating with means on said table to vary the longitudinal travel of the yoke to cause the shaft to rotate independently of said motor in conformance with the pitch of the tool being ground.

3. In a tool grinder, a base, a table mounted for reciprocating movement on said base, a pair of spaced pedestals formed on said table, an arbor shaft having a fixed axial position relative to said table and rotatably mounted between said pedestals and adapted to receive a tool to be ground, said arbor shaft having a helical cam therein, a collar mounted about said shaft and axially movable thereon, a cam follower projecting inwardly from said collar and into engagement with said cam, a gear fixed concentrically on said collar to drive the shaft through said follower, a motor mounted adjacent said collar, a gear carried by said motor and in engagement with said first named gear, a yoke supporting said motor and engaging said collar to move the collar longitudinally relative to said arbor shaft and effect movement of the follower in the cam to vary the rotation of the arbor shaft independently of said motor as the table reciprocates, and means, including an element having pure longitudinal movement engageable with an element having pure transverse movement, to vary the longitudinal travel of the yoke to cause the shaft to rotate independently of said motor in conformance with the pitch of the tool being ground.

4. In a grinder, a base, a table slidably mounted on said base, an arbor shaft including means to receive a multi-edged tool having helical cutting edges in one end thereof, said arbor shaft being mounted to reciprocate with said table on said base, means to effect continuous rotation of the shaft, a rotating grinding wheel mounted adjacent one end of the arbor shaft, means engaging the arbor shaft to vary the rotation thereof in accordance with the axial reciprocation of the shaft, and means to move the arbor shaft toward and away from said grinding wheel periodically during the grinding.
